UNITED STATES PATENT OFFICE.

HENRY A. PRUSSER, OF WILLOW, CALIFORNIA.

DESIGN FOR AN AUTOMOBILE RADIATOR-CAP OR LIKE ARTICLE.

46,448.

Specification for Design.

Patented Sept. 22, 1914.

Application filed June 30, 1914. Serial No. 848,313. Term of patent 7 years.

To all whom it may concern:

Be it known that I, HENRY A. PRUSSER, a citizen of the United States, residing at Willow, in the county of Glenn and State of California, have invented a new, original, and ornamental Design for Automobile Radiator-Caps or like Articles, of which the following is a specification, reference being had to the accompanying drawing, forming part thereof.

The figure is a front elevation of an automobile radiator cap embodying the design.

I claim:—

The ornamental design for an automobile radiator cap or like article, substantially as shown.

HENRY A. PRUSSER.

Witnesses:

EDWARD E. AVERY,

WALTER RABBITT.
